US00D844164S

(12) **United States Design Patent** (10) Patent No.: **US D844,164 S**
(45) Date of Patent: **** Mar. 26, 2019**

(54) **BRIDGE**

- (71) Applicants: **thyssenkrupp AG**, Essen (DE); **ThyssenKrupp Steel Europe AG**, Duisburg (DE)
- (72) Inventors: **Andreas Cott**, Düsseldorf (DE); **Ingo Rogner**, Ingolstadt (DE); **Lothar Patberg**, Moers (DE); **Marcus Rauhut**, Muelheim (DE); **Erik Hilfrich**, Düsseldorf (DE); **Michael Bruggenbrock**, Rosendahl (DE); **Ralf Stegmeyer**, Medebach (DE); **Stephan Drews**, Mönchengladbach (DE); **Thomas Flaskamp**, Duisburg (DE)
- (73) Assignees: **thyssenkrupp Ag** (DE); **ThyssenKrupp Steel Europe AG** (DE)

(**) Term: **15 Years**

(21) Appl. No.: **29/608,252**

(22) Filed: **Jun. 20, 2017**

(30) **Foreign Application Priority Data**

- Dec. 20, 2016 (EM) 003529247
- (51) LOC (11) Cl. **25-03**
